LENS PANEL HINGE PIN

Charles O. Hughes, St. Louis, and Thomas Akin, Clayton, Mo., assignors to Emerson Electric Co., St. Louis, Mo.

Filed July 8, 1969, Ser. No. 18,117

Term of patent 14 years

Int. Cl. D8—03

U.S. Cl. D8—259

Fig 2

Fig 1

Fig 3

FIG. 1 is a perspective of a lens panel hinge pin showing my new design, the fragmentary lens panel being shown in broken line for illustrative purposes only;

FIG. 2 is a side elevation thereof as seen from the undisclosed side of FIG. 1; and

FIG. 3 is a view in end elevation of the lens panel hinge pin of FIGS. 1 and 2.

We claim:

The ornamental design for lens panel hinge pin, as shown and described.
